IMPEDANCE REGULATING SYSTEM

Horst Rothe, Berlin, Germany, assignor to Tele-funken Gesellschaft für Drahtlose Telegraphie m. b. H., Berlin, Germany, a corporation of Germany

Application May 6, 1930, Serial No. 450,111
In Germany May 11, 1929

22 Claims. (Cl. 178—44)

The present invention relates to variable impedances and more particularly to means for producing inertialess variable capacitive or inductive impedances.

5 For modulating, regulating and similar purposes, recourse is had frequently in radio technics to impedances the value of which are varied within certain limits by auxiliary potentials or currents rather than mechanically. It often happens that impedances must be regulated or adjusted from a remote point by way of a line, say, for modulating or regulating a transmitter station or some other alternating current apparatus.

For all of these purposes, as far as applicant 15 is aware, only iron-cored choke coils have heretofore been available, the inductance thereof being varied by varying the biasing magnetizing current of the iron-core. However, whenever very high frequencies are involved, such coils are 20 unserviceable because of the presence of the iron core, not to mention the further disadvantages that they involve comparatively high losses, and that their time constants are high. An object 25 of the present invention is to disclose ways and means of creating both capacities as well as inductances suited also for extremely high frequencies, and which follow changes in electrical conditions practically without inertia, such variations, if desired, being accomplished from a remote point.

Other objects of the invention will be apparent from the following detailed specification of the invention when read in connection with the drawing, in which,

35 Fig. 1 illustrates generally and schematically the principles involved in the invention; and,

Figs. 2 through 6 illustrate practical examples of some of the uses to which the invention may 40 be put.

It is known that in a thermionic tube 1 comprising a control grid (Fig. 1) and whose plate circuit contains the apparent impedance R_a , a complex resistance R_{sch} is transferred between 45 control grid and filament of the tube, when the grid and the plate are associated by a resistance R_{ga} , the size of the latter being readily determined mathematically if desired. In accordance with this disclosure the resistance transferred between grid and filament as a circuit element is utilized to obtain the desired variation, the variation of said quantity being insured by varying the plate resistance R_a or the internal tube resistance R_i between the anode 50 and filament, or both, this being accomplishable

by simple means. The variations of resistance R_a or R_i may follow modulating potentials.

The nature of this transferred resistance and its variation shall be explained by a number of practical examples:

5 Fig. 2 illustrates the simplest circuit scheme comprising a capacity C_{ga} between grid and plate which may be the capacitance inherent in the grid plate association, though, if necessary, the plate grid capacity may be increased by the aid of an external supplementary capacity. In the plate circuit there is an invariable ohmic resistance R_a to which is shunted (arranged in parallel) the natural capacity inherent in the tube between the cathode and the plate. The 10 variation of the transferred resistance R_{sch} is effected by varying the grid biasing potential of the tube with the result that the working point is shifted to a point along the tube characteristic having either a higher or a lower internal 15 tube resistance. The biasing potential may be applied from any source to E_g .

Fig. 3 illustrates another conceivable circuit arrangement in which between the grid and the plate of the tube 1 is a capacity C_{ga} . The plate 20 resistance R_a in this modification consists of the cathode to anode resistance of tube 2. Hence, it is also in this instance predominantly ohmic in nature, and by varying the grid biasing potential E_g of the tube 2 it can be altered within wide 25 limits. It can be easily found by calculation that the resistance transferred between grid and filament in tube 1 consists of a capacity and a positive ohmic resistance in shunt relation thereto, the size of both components being predicated 30 upon R_a . The theoretical liminal values between which the capacity may be changed when varying R_a amount to 35

$$C_{ga} \text{ and } C_{ga} \left(1 + \frac{1}{D} \right)$$

40 respectively where D denotes the reciprocal amplification factor. What must be borne in mind in this connection is that in parallel relation to this transferred resistance there exists the inherent or natural grid reactance (ohmic resistance and capacity). A more effective change of 45 R_{sch} is attainable by the simultaneous alteration of R_a and R_i in opposite senses.

On account of the inherent capacitance between filament and plate of every tube, the circuit schemes shown in Figs. 2 and 3 are unsuited for extremely high frequencies. Where such high frequencies are dealt with, the plate 50 resistance (impedance) as shown in Fig. 4, must 55

- consist of an oscillation circuit the damping of which is influenced by means of tube 2. Also for this case the resistance Rs_{ch} can be calculated as above indicated. The capacitive component then changes also inside the limits above given, while the ohmic component must assume either positive or negative values according to whether the impedance of the oscillation circuit is ohmic, reactive or inductive.
- 10 In cases where a variable inductance is required, as shown in Fig. 5, grid and plate must be associated by an inductance in series as shown with a blocking condenser to block out the plate direct current from the grid.
- 15 An inductive reactance between grid and filament is obtainable also by means of a neutralized circuit scheme as illustrated in Fig. 6. In case the condenser CN is greater than the inherent grid plate capacity C_{ga} , the resistance transferred in this arrangement, Rs_{ch} , contains an inductive and a negative ohmic component. This phase shift of the transferred resistance is obtained by that the transferred resistance is connected with a point of the plate circuit where the potential presents 25 a phase displacement angle of 180 degrees in relation to the plate potential.
- I claim:
1. A device for producing an impedance which may be varied linearly in accordance with potential variations comprising, a thermionic tube, having a control grid, a cathode and an anode, an impedance connected between said anode and control grid, a variable resistance connected in parallel with the internal impedance of the tube, 30 between said anode and cathode of said tube, and a device connected with said variable resistance and energized by said potential variations for varying said resistance in accordance with said potential variations whereby resistance effects are produced between said control grid and cathode which are linear with respect to said potentials.
  2. Means for producing an impedance which varies linearly with respect to modulation potential variations comprising, a thermionic tube having a control grid, a cathode and an anode, a reactance connected between said anode and control grid, and a variable resistance connected in parallel with the internal impedance between 35 the anode and cathode of said tube comprising an additional thermionic tube having its anode electrode connected with the anode of said first named tube and its input electrodes connected to a source of modulating potentials, whereby impedance effects which vary in accordance with said modulating potentials are produced between the control grid and cathode of said first named tube which are linear with respect to said modulating potentials.
  3. A device for producing an electrical characteristic which may be varied linearly in accordance with potential variations comprising, a thermionic tube having a control grid, a cathode and an anode, a capacity connected between said anode and control grid, a reactance connected in parallel with the anode to cathode impedance of said tube, and a variable resistance connected in parallel with the internal impedance between the anode and cathode of said tube comprising an additional tube having its anode to cathode impedance connected in parallel to said reactance and its control grid connected to a source of potentials which vary, whereby resistance effects 70 are produced between said control grid and

cathode of said first named tube which are linear with respect to said potentials which vary.

4. A device for producing an electrical characteristic which may be varied directly in accordance with modulating potential variations comprising, a thermionic tube having an anode, a cathode and a control grid, an inductance connected between said anode and said control grid, a tuned circuit connected with said anode, said tuned circuit being in effect in parallel with the internal resistance between said anode and said cathode, an additional thermionic tube having its output electrodes connected in parallel with said tuned circuit, and means for applying modulating potentials to the input electrodes of said additional tube, whereby a resistance effect proportional to said modulating potentials is produced between the control grid and cathode of said first named tube.

5. A device as recited in claim 4 in which said inductance connected between the control grid and anode of said first named tube is in series with a capacity.

6. The method of operating a triode as a variable impedance element in a circuit including a reactive coupling between the grid and anode elements of said triode, and a resistance connected between the cathode and anode thereof, which comprises varying said resistance to produce consonant variations of the effective anode-grid reactance of said triode.

7. The method of operating a triode as a variable impedance element in a circuit including a reactive coupling between the grid and anode elements of said triode, and a resistance connected between the cathode and anode thereof, which comprises cyclically varying said resistance to produce consonant variations of the effective anode-grid reactance of said triode.

8. A circuit of variable reactance comprising a vacuum tube including a cathode, an anode, and a grid and having reactive coupling between said anode and grid, and a second vacuum tube connected as an output resistor between the anode and cathode of said first tube, said second tube being variable in resistance to produce consonant variations in reactance between the cathode and grid of said first tube.

9. A circuit of variable reactance comprising a vacuum tube including a cathode, an anode, and a grid, a reactive element connected between said grid and anode, and a second vacuum tube connected as an output resistor between the anode and cathode of said first tube, said second tube being variable in resistance to produce consonant variations in reactance between the cathode and grid of said first tube.

10. A circuit of variable reactance comprising a vacuum tube including a cathode, an anode, and a grid, a capacitance externally connected between said grid and anode, and a second vacuum tube connected as an output resistor between the anode and cathode of said first tube, said second tube being variable in resistance to produce consonant variations in reactance between the cathode and grid of said first tube.

11. A circuit of variable reactance comprising a vacuum tube including a cathode, an anode, and a grid, an inductance connected between said cathode and anode, and a second vacuum tube connected as an output resistor between the anode and cathode of said first tube, said second tube being variable in resistance to produce consonant variations in reactance between the cathode and grid of said first tube.

12. A variable reactance circuit comprising a vacuum tube including a cathode, an anode, and a grid, and having reactive coupling between said anode and grid, a second vacuum tube connected as an output resistor between said anode and cathode, and means for cyclically varying the effective resistance of said second tube to produce corresponding variations in the effective cathode-grid reactance of said first tube. 5
13. The method of employing an amplifier tube having input and output circuits to vary the impedance of said input circuit which comprises reactively connecting said input and output circuits, discarding the power developed in said output circuit, and varying said output circuit to vary the reaction thereof upon said input circuit. 10
14. The method of operating a tube as a variable impedance element in a circuit including an impedance coupling external to the tube between the grid and anode elements of said tube, and an impedance connected between the cathode and anode thereof, which comprises varying said last named impedance to produce consonant variations of the effective anode grid impedance to said tube. 15
15. A circuit of variable impedance comprising a vacuum tube including a cathode, an anode, and a grid, an impedance element connected between said grid and anode, and a second vacuum tube connected as an output impedance between the anode and cathode of said first tube, said second tube being variable in impedance to produce consonant variations in impedance between the cathode and grid of said first tube. 20
16. A variable electronic condenser unit comprising an electron discharge tube having at least a cathode, grid and anode, the grid circuit of the tube comprising the condenser, reactive means common to the grid and anode circuits of the tube for providing a predetermined capacity in said condenser, and means for adjusting an electrical characteristic of the unit for producing desired changes in the value of said capacity. 25
17. A variable electronic condenser unit comprising an electron discharge tube having at least a cathode, grid and anode, the grid circuit of the tube comprising the condenser, condensive means common to the grid and anode circuits of the tube for providing a predetermined capacity in said condenser, and means for adjusting an electrical characteristic of the unit for 30
- producing desired changes in the value of said capacity. 5
18. An adjustable condenser unit comprising a tube having at least a cathode and two cold electrodes, the circuit between the cathode and one of the cold electrodes comprising the condenser, a capacitance common to both of said cold electrodes for producing a desired capacity value in the said condenser, and means for varying an electrical characteristic of the unit for 10 changing the said value. 10
19. An adjustable condenser unit comprising a tube having at least a cathode and two cold electrodes, the circuit between the cathode and one of the cold electrodes comprising the condenser, a capacitance common to both of said cold electrodes for producing a desired capacity value in the said condenser, and means for varying an electrical characteristic of the unit, such as the amplification factor of the tube, for 15 changing the said value. 15
20. A variable condenser unit comprising a tube provided with a cathode, plate and control electrode, the circuit between the cathode and control electrode comprising the condenser, a condenser connected between the plate and control electrode to augment the capacity of said condenser, and means for varying the space current flow in a predetermined manner for producing desired variations in the said capacity. 20 30
21. A variable condenser unit comprising a tube provided with a cathode, plate and control electrode, the circuit between the cathode and control electrode comprising the condenser, a condenser connected between the plate and control electrode to augment the capacity of said condenser, a load in the plate circuit of the tube comprising inductance and resistance, and means for varying the space current flow in a predetermined manner for producing desired variations in the said capacity. 35 40
22. An adjustable voltage operated capacitance comprising a tube provided with a cathode and at least a grid and plate, the capacity between the grid and cathode comprising the said capacitance, auxiliary capacitance being provided between the grid and plate to augment the value of said first capacitance, and means for adjusting the space current flow of the tube in a predetermined manner for producing desired variations in the value of said first capacitance. 45 50
